UNITED STATES PATENT OFFICE.

GEORGE W. LORD, OF MATTAPAN, MASSACHUSETTS.

SMOKE-CONSUMING DEVICE.

SPECIFICATION forming part of Letters Patent No. 552,847, dated January 7, 1896.

Application filed March 30, 1895. Serial No. 543,794. (No model.)

To all whom it may concern:

Be it known that I, GEORGE W. LORD, a citizen of the United States, and a resident of Mattapan, in the county of Suffolk and State 5 of Massachusetts, have invented new and useful Improvements in Smoke-Consuming and Combustion Devices, of which the following, taken in connection with the accompanying drawings, is a specification.

10 This invention relates to an improved smoke-consuming and combustion device for steam-boiler, puddling, or other furnaces, and it is carried out as follows, reference being had to the accompanying drawings, wherein—

15 Figure 1 represents a front elevation of a steam-boiler provided with my invention. Fig. 2 represents a vertical section of the same. Fig. 3 represents a detail bottom plan view of the adjustable air-supply-regulating device, 20 and Fig. 4 represents a detail side elevation of Fig. 3.

Similar letters refer to similar parts wherever they occur on the different parts of the drawings.

25 In the drawings, A represents the furnace or fire-pot of a steam-boiler B, as usual.

C represents the end brick wall, immediately above the furnace-doors D D.

E represents the grate, with its ash-pit F 30 and ash-doors G G, as is common in steam-boiler or other furnaces.

H is the usual cast-iron end plate, to which the doors D D and G G are hinged, as shown.

From the steam-space of the boiler I carry 35 a steam-supply pipe I, provided with a valve or cut-off i, as shown in Fig. 1. Through perforations in the front plate H are inserted one or more conductor-pipes or ejector-chambers K, the inner ends of which are screw-threaded, 40 as shown at k, and provided with a fastening-nut k', as shown in Fig. 2, by which arrangement the pipe or pipes K may be firmly secured to the plate H and adjusted in position relative to the latter as may be desired. To 45 one side of the pipe K and in open communication with it is secured an air-inlet branch L, having an internal screw-thread l in its upper open end, into which is screwed the adjustable air-supply-regulating device, consisting

50 of a cap M having a series of air-supply perforations m m, as shown in Figs. 2, 3, and 4.

The perforated cap M is provided with skel-

eton wings or ribs M', the edges of which are screw-threaded and adjustable in the internal screw-threaded portion l of the air-supply pipe L, as shown in Fig. 2.

The lower end of the pipe I enters the outer end of the ejector-chamber K, and within the latter is attached to said pipe I a suitable steam-ejector N of any well-known form or 60 construction.

Within the pipe K, I arrange back of the ejector N a lining O, made of asbestos cloth or other suitable fire-resisting or soft material, so as to deaden the noise caused by forcing the 65 steam and air through said pipe K, as fully represented in Fig. 2.

To the inner end of the pipe K is loosely screwed the curved or bent deflector-pipe P, through which the mixed air and steam from the pipes I and L is forced at a proper angle against the fuel, and thereby caused to intermix intimately with the unconsumed products from the fire, by which a thorough combustion of such products takes place, as well as 75 causing the smoke to be consumed.

The steam which is forced by the ejector N through the pipe or chamber K produces a vacuum within the latter, causing the air to be drawn in through the pipe L and its air-regulating device.

When the cap M is screwed down against the end of the pipe L, the perforations m m serve as means for admitting the air to the pipe L. If it is desired to increase the air supply all that is necessary to do is to unscrew the cap M more or less from the pipe L, by which an increased volume of air is conducted into the pipe L, between the radial wings M' M', as 85 fully shown in Fig. 2.

It will thus be seen that the supply of air to the chamber K can be regulated to a nicety simply by adjusting the position of the cap M relative to the mouth of the air-supply pipe L, as above described. The supply of steam 95 to the ejectors may be also regulated by adjustment of the valve or cut-off i on the steam-pipe I.

I prefer to use with this my invention an ejector having means for properly regulating the size of its discharge-opening and thus regulating the pressure and volume of steam ejected.

Among the advantages of this my invention

may be mentioned consumption of smoke, a thorough combustion of the products of the fuel, and an increase of heat in the furnace and consequent saving of fuel.

Having thus fully described the nature, construction, and operation of my invention, I wish to secure by Letters Patent and claim—

1. In a smoke consuming and combustion device, in combination an ejector chamber having a steam ejector arranged within it, an air supply pipe leading to the ejector chamber and having an adjustable air inlet, an asbestos-cloth or equivalent lining within the ejector chamber and a deflector pipe connected to the latter and to the interior of the furnace substantially as specified.

2. In a smoke consuming and combustion device an ejector chamber communicating with the interior of the furnace and having a steam ejector arranged within it, combined with an air pipe connected to the ejector chamber and a regulating cap having perforations

and screw threaded wings said wings projecting downward from the under side of the cap adapted to work in the screw threaded end of the said air pipe substantially as and for the purpose set forth.

3. In a smoke consuming and combustion device an air supply pipe having an internal screw thread at its outer end combined with a cap having perforations and radial wings screw threaded at their outer edges said wings projecting downward from the under side of the cap and adapted to screw into the air supply pipe substantially as and for the purpose set forth.

In testimony whereof I have signed my name to this specification, in the presence of two subscribing witnesses, on this 27th day of March, A. D. 1895.

GEORGE W. LORD.
